UNITED STATES PATENT OFFICE.

SAMUEL BESKIN, OF NORFOLK, VIRGINIA.

COIN-CONTROLLED MECHANISM FOR VENDING-MACHINES.

1,211,528.

Specification of Letters Patent.

Patented Jan. 9, 1917.

Application filed February 25, 1916. Serial No. 80,505.

To all whom it may concern:

Be it known that I, SAMUEL BESKIN, a citizen of the United States, residing at Norfolk, in the county of Norfolk and State 5 of Virginia, have invented new and useful Improvements in Coin-Controlled Mechanism for Vending-Machines, of which the following is a specification.

This invention relates to improvements in 10 coin controlled mechanism for vending machines and has particular application to mechanism for use in connection with motor driven automatic ticket selling machines, such as are employed for dispensing tickets 15 in moving picture theaters and the like.

In carrying out the present invention, it is my purpose to provide coin controlled mechanism of the class described which may be readily operated upon the application 20 of a coin of the proper denomination and whereby the automatic ticket selling machine may be set in operation by the purchaser of the ticket, thereby eliminating the necessity of employing an operator for the ticket 25 selling machine.

It is also my purpose to provide mechanism of the class described which may be installed and maintained at small cost, which when once installed will operate efficiently 30 and effectively for its intended purpose and which will embody comparatively few parts and these so correlated and arranged as to reduce the possibility of derangement to a minimum.

With the above and other objects in view, the invention consists in the construction, combination and arrangement of parts hereinafter set forth in and falling within the scope of the claims.

In the accompanying drawings; Figure 1 is a perspective view of coin controlled mechanism constructed in accordance with the present invention, the same being shown as applied to an automatic ticket selling machine. Fig. 2 is a vertical sectional view through the casing, the mechanism being shown in front elevation. Fig. 3 is a sectional view taken at right angles to Fig. 2 showing the parts in inactive position. Fig. 4 is a similar view showing the parts in active position. Fig. 5 is a horizontal sectional view on the line 5—5 of Fig. 3. Fig. 6 is an enlarged fragmentary vertical sectional view through the coin receiver. Fig. 7 is a sectional view on the line 7—7 of Fig. 2. Figs.

8, 9 and 10 are perspective views of details of the invention.

Referring now to the drawings in detail, 1 designates a substantially rectangular vertical casing embodying a bottom wall or 60 base plate 2, front and back walls and vertical side walls uprising from the bottom wall or base plate 2, and a top wall 3. Arranged within the casing 1 between the side walls thereof is a vertical partition 4 extending from the front wall to the back wall and dividing the casing into compartments 65 5 and 6. The front and back walls of the compartment 5 are preferably formed of glass or other transparent material, as 70 clearly illustrated in Figs. 1 and 5 of the drawings.

The rear wall of the compartment 6 is removable and carries the coin controlled mechanism and secured to the upper portion 75 of the inner face of the rear wall of the compartment 6 is a block 7. This coin controlled mechanism comprises a vertical plate 8 having its upper end connected to the block 7 by means of a hinge 9 and the lower end 80 terminating adjacent to the lower end of the block and formed on the lower end of the plate 8 and depending therefrom contiguous to one side edge of the plate is an arm 10. Formed in the top wall 3 of the casing 1 85 above the compartment 6 is a coin slot 11 opening onto the front face of the plate 8. Formed on the front face of the plate 8 at one edge thereof is a rib 12 contiguous to one end wall of the slot 11, while formed on 90 said face of the plate 8 adjacent to the other end thereof is a rib 13 disposed contiguous to the other end of the slot 11 and these ribs 12 and 13 are spaced apart a sufficient distance to permit a coin to pass between the same. Suitably fastened to the edge of the block 7 adjacent to the partition 4 is a casting 14 having the upper end thereof disposed adjacent to the lower end of the rib 12, and the bottom portion offset from the 95 top portion at the center of such casting and immediately below the lower end of the plate 8. Formed in the upper portion of the casting 14 is a slot 15 alining with a slot 16 formed in the partition 4 whereby communication may be established between the slot 15 and the compartment 5. Secured to the casting 14 and partially closing the slot 15 100 is a guard plate 17. Pivoted upon the front face of the swinging plate 8 immediately 105

110

below the lower end of the rib 13 is a weight 18, while pivoted between its ends upon the front face of the plate 8 below the weight 18 is a lever 19 having the upper end thereof 5 designed to engage the weight 18 and the lower end formed with a laterally extending foot 20 disposed below the bottom extremity of the plate 8. The weight 18 bears upon the upper end of the lever 19 and acts to hold 10 such lever normally in a vertical position and the portion of the lever 19 above the pivot or fulcrum thereof is bowed slightly so that when a coin is dropped through the slot 11 and down the plate 8 between the ribs 15 12 and 13, such coin will be brought to rest by the bowed portion of the lever and the plate 17 and as the coin wedges in between the plate 17 and the bowed portion of the lever 19 the latter is swung about its pivotal 20 connection with the plate 8 against the action of the weight 18 to move the foot 20 from the full line position in Fig. 2 of the drawings to the dotted line position.

Pivoted upon the lower offset portion of 25 the casting 14 is a sector 21 having the lower edge formed with teeth 22 and the upper edge formed to provide a cam 23. Formed on the edge of the sector and spaced apart from the cam is an inclined tongue 24. Also 30 pivoted upon the lower offset portion of the casting 14 below the sector 21 is a toothed sector 25 meshing with the teeth on the sector 21 and formed with a weight 26 and a hand lever 27. The lever 27 projects 35 through a slot 28 formed in the front wall of the compartment 6.

Normally, the foot end of the lever 19 is 40 out of the path of movement of the cam edge of the sector 21. When, however, the lever is swung under the action of a coin, as shown in Fig. 2 of the drawings, and as hereinbefore described, the foot end of the lever is 45 brought into the path of movement of the cam edge of the sector so that when the lever 27 is pulled down and the sectors 25 and 21 rotated against the action of the weight 26, the cam edge 23 of the sector 21 engages the foot end of the lever 19 and 50 swings the plate 8 bodily toward the back wall of the compartment 6. A suitable form 55 of spring 29 is interposed between the block 7 and the back face of the plate 8 and this spring acts to hold the plate normally in vertical position and to restore the same to such position succeeding the swinging thereof under the action of the lever 27 and the sectors. In this swinging of the plate, a 60 corresponding motion is imparted to the arm 10 depending from such plate and disposed in the path of the arm 10 is a roller 30 journaled upon an arm 31 pivoted upon a bracket 32 fastened to the back wall of the compartment 6. Connected to the same end of the arm 31 as the roller 30 is one extremity of a link 33 and the other end of the link

33 is pivotally connected with one end of a lever 34 fulcrumed between its ends upon a bracket 35 carried by a horizontal casting 36 secured to the back wall of the compartment 6.

37 designates a vertically movable plunger 70 slidably mounted in a bearing 38 and having the lower end thereof working in an opening 39 formed in the base plate 2. Surrounding the plunger 37 between the bearing 38 and 75 a collar 40 fixed to the plunger above the bearing is a coiled expansion spring 41 acting to hold the plunger normally at its limit of upward movement.

The lower end of the arm 10 works in a 80 slot formed in the casting 36 and disposed at the side of the arm opposite from the roller 30 is a stop 42 carried by the casting 36 and designed to limit the swinging movement of the arm 10 and the plate 8 under the 85 action of the spring 29.

In the swinging of the plate and arm under the action of the sectors, the arm 10 engages the roller 30 and, through the medium of the link 33 and the lever 34, slides the plunger 37 downwardly against the action of the spring 41. As soon as the cam edge 23 of the sector 21 rides out of engagement with the foot end of the lever 19, the tongue 24 kicks the lever 19 back to normal position, thereby releasing the plate and upon the release of the plate, 29 reacts to restore the plate and the arm 10 to normal position, while the spring 41 reacts to restore the plunger 37, the lever 34 and the lever 33 to 95 normal position, so that the above cycles of operation may be repeated upon the insertion of another coin in the mechanism. In the swinging of the plate 8, the coin is relieved of the holding influence of the plate 105 17 and falls through the slots 15 and 16.

As previously stated, this coin controlled mechanism is designed for use in connection with motor driven automatic ticket selling machines of the type whereby one or more 110 tickets may be delivered to the purchaser upon the depression of a button. My improved coin controlled mechanism is seated upon this ticket selling machine as clearly illustrated in Fig. 1 of the drawings and the 115 plunger 37 is disposed in line with the controlling button of the machine, as shown in Figs. 3 and 4 of the drawings, and when the parts of the coin controlled mechanism are in normal position, as in Fig. 3, the 120 lower end of the plunger is spaced apart above the button of the ticket selling machine, while when the parts of the coin controlled mechanism are in active position, as in Fig. 4, the plunger 37 depresses the button 125 so that the prescribed number of tickets will be delivered to the purchaser.

In the present instance, the compartment 5 is divided into upper and lower chambers by means of a horizontal transparent parti- 130

tion 42 pivoted for swinging movement within the compartment 5 and under the control of a lever 43 pivoted between its ends to the partition 4 and having one end arranged below the partition 42 and the other end projecting through a slot formed in the back wall of the compartment 5. This partition 42 is adapted to receive coins that are discharged through the slot 16 and these coins may be delivered to the bottom chamber of the compartment 5 by swinging the partition 42 under the action of the lever 43. The front portion of the plate 8 is preferably covered by means of a strip 44, clearly shown in Fig. 10 of the drawings.

While I have herein shown and described the preferred form of my invention by way of illustration, I wish it to be understood that I do not limit or confine myself to the precise details of construction herein described and delineated, as modification and variation may be made within the scope of the claims and without departing from the spirit of the invention.

I claim:

1. In mechanism of the class described, a vertically movable plunger, means for moving said plunger, a plate adapted for swinging movement designed to operate said means to move said plunger, means for

swinging said plate, and a coin controlled lever controlling the connection between said swinging means and said plate.

2. In mechanism of the class described, a vertically movable plunger, means for moving said plunger, a plate adapted for swinging movement and designed to operate said means to move said plunger, a lever pivoted upon said plate and normally disposed in inactive position and capable of movement to active position by the weight of a coin, and means adapted to engage said lever when in active position to swing said plate.

3. In mechanism of the class described, a vertically movable plunger, means for moving said plunger, a plate adapted for swinging movement and designed to operate said means to move said plunger, a lever pivoted upon said plate and normally disposed in inactive position and capable of movement to active position by the weight of a coin, and manually operable means adapted to engage said lever to swing said plate and to automatically release said lever.

In testimony whereof I affix my signature in presence of two witnesses.

SAMUEL BESKIN.
